UTILITY DERRICK

Royce Kershaw, Montgomery, Ala.

Application February 12, 1951, Serial No. 210,489

2 Claims. (Cl. 212—65)

This invention relates to a utility derrick and has for an object the provision of a derrick which shall be particularly adapted for use on railroads in the handling of various machines and materials used in construction and repair work.

Another object of my invention is to provide a rail derrick having a supporting vehicle which is of triangular shape as viewed in plan thereby providing a vehicle which is exceptionally light yet strong in construction and one adapted for quick and easy removal from the track.

A further object of my invention is to provide a rail derrick of the character designated which shall be adapted for quick and easy dismantling and erection for operation at either side of the railroad track with the boom thereof extending in any desired direction.

A still further object of my invention is to provide a vehicle supported derrick of the character described having improved means for anchoring the vehicle to the rails when the derrick is to be used.

A derrick embodying features of my invention is illustrated in the accompanying drawing, forming a part of this application, in which:

Fig. 1 is a plan view showing the derrick in operating position on a railroad track, with certain parts broken away and in section for the sake of clarity;

Fig. 2 is a side elevational view showing the derrick ready for operation;

Fig. 3 is a plan view, showing the derrick assembled with the boom over the opposite side of the railroad track from that shown in Fig. 1 and with the boom extending in the same direction as shown in Fig. 1;

Fig. 4 is an enlarged detail view taken along the line IV—IV of Fig. 2;

Fig. 5 is a side elevational view showing my improved grapple for anchoring the vehicle to the rails with the grapple in raised position;

Fig. 6 is a sectional view taken along the line VI—VI of Fig. 5, the grapple being shown in raised position in full lines and in clamping position in dotted lines; and

Fig. 7 is a sectional view taken along the line VII—VII of Fig. 6.

Referring now to the drawing for a better understanding of my invention I show a vehicle triangular in shape as viewed in plan, comprising horizontally extending frame members 10, 11 and 12 which may be made of tubular steel, channels or the like. The frame member 10 extends in a direction substantially normal to the longitudinal axis of the frame member 11. Also, the frame member 10 is substantially equal in length to the frame member 11. Secured to the frame member 10 at the end thereof adjacent the frame member 11 is the lower end of a vertically extending mast 13. Mounted on opposite sides of the mast 13 adjacent the lower end thereof and extending outwardly therefrom in a direction normal to the longitudinal axis of the frame member 10 are clevises 14 and 16. The end of the frame member 11 adjacent the clevis 14 is preferably flattened or pinched to form a vertically extending ear or lug 17 of a size to fit within the jaws of the clevis 14. An opening is provided in the lug 17 to receive a bolt 18, thereby detachably securing the frame member 11 to the clevis 14.

Mounted adjacent the end of the frame member 10 opposite the mast 13 are clevises 19 and 21, angularly disposed to each other and opening toward the mast end of frame member 10. Mounted adjacent the end

2

of the frame member 11, opposite the flattened end 17 thereof are angularly disposed, inwardly opening clevises 22 and 23. The frame member 12, forming the hypotenuse of the triangular frame, extends between and is 5 detachably secured to the clevises 19 and 22. The ends of the frame member 12 are flattened to form vertically extending lugs 24 and 26 having openings therein for receiving bolts 27 and 28. The clevis members 16, 21 and 23 are used for a purpose to be described herein- 10 after.

Secured beneath the mast 13 and the adjacent end of the frame member 10 is a box-shaped wheel housing 29 having an open bottom. Rotatably mounted in the housing 29 on a transversely disposed axle 31 is a double flanged track-engaging wheel 32. Mounted beneath the end of the frame member 10 opposite the mast 13 is a box-shaped wheel housing 33 similar in all respects to the housing 29. Rotatably mounted in the housing 33 on a transversely disposed axle 34 is another double flanged, track-engaging wheel 36. Mounted beneath the end of the frame member 11, adjacent the clevis members 22 and 23 is a box-shaped wheel housing 37 similar to the housings 29 and 33. Rotatably mounted in the box housing 37 on a transversely disposed axle 38, 15 is a track-engaging wheel 39 which may be double or single flanged.

Secured to the mast 13 adjacent the top thereof is the upper end of a downwardly extending brace 41. The lower end of the brace 41 is secured to the top of the housing 33. Secured to the mast 13 adjacent the top thereof are oppositely disposed clevis members 42 and 43 which extend in a direction parallel to the frame member 11. Detachably connected to the clevis 42 is the upper end of a downwardly extending brace 44. The lower end of the brace 44 is fixedly secured to the top of the housing 37.

The derrick structure associated with the vehicle comprises a bracket 46 secured to the mast 13 adjacent the lower end thereof. Pivotal mounted on the bracket 46 is the lower end of a boom 47 which is removably secured in place by means of a pivot pin 48. The outer end of the boom 47 is provided with a pulley 49 over which passes a cable or rope 51. The inner end of the cable 51 is secured to a winch 52 carried by the boom and which may be operated by hand or any other suitable source of power. The boom 47 is stabilized by a Y-shaped guy rod 53 having its legs detachably connected to brackets 54 on the boom and its inner end connected to the top of the mast by means of a clevis and pin connection 56. It will be seen that the boom 47 is capable of moving in an arc upon the vertically extending mast 13, and that by operating the winch 52 loads connected to a hook block 55 in the bight of the cable may be readily lifted.

55 The vehicle is anchored to the rails 57 and 58 by means of my improved grapple 59 to be described hereinafter. Two grapples are provided, one being mounted on the housing 33 and the other being mounted on the housing 37, thus anchoring the ends of the frame members 10 and 11 opposite the mast 13 to the rails 57 and 58, respectively, of the railroad track.

In Fig. 1 of the drawing I show the boom 47 positioned over the rail 57. If it is desired to position the boom 47 over the opposite rail 58 of the track and have the boom extend in a direction opposite to that shown in Fig. 1, the vehicle is merely turned around and anchored into position by the grapples 59. However, if it is desired to position the boom over track 57 but have it extend in a direction opposite to that shown in Fig. 1 or to position the boom over track 58 and have it extend in the same direction as shown in Fig. 1, the vehicle is dismantled and erected in the manner shown in Fig. 3 of the drawing. For example, to position the boom over the rail 58 as shown in Fig. 3 the frame member 12 is disconnected from the clevises 19 and 22. The frame member 11 is disconnected from the clevis 14 and the brace 44 is disconnected from the clevis 42. The frame member 10 is placed over the rail 58, as shown, and the frame member 11 is turned around so that the vertical flattened end 17 thereof fits in the clevis. The frame member 12 is then secured to the clevises 21 and 23 and

the upper end of brace 44 is secured to the clevis 43. It will be noted that to position the boom 47 over the rail 57 in a direction opposite to that shown in Fig. 1, the frame member 10 is turned around on the rail 57. The vertically extending portion 17 of the frame member 11 is then secured to clevis 16, the upper end of the brace 44 is secured to clevis 43 and the frame member 12 is secured to the clevises 21 and 23.

The grapple assembly preferably comprises a stationary rod 61 secured to the top of the box-shaped housing 33 or 37, as the case may be, as by welding at 62. Slidably mounted on the rod 61 is a block 63 having a through opening 64 disposed near one end thereof. The upward movement of the block 63 is restricted by means of a limit pin 65. Laterally extending, spaced slots or grooves 66 and 67 are provided in the lower portion of the block 63 on the side thereof opposite the opening 64. Pivotally mounted in the slots 66 and 67 on a common pin 68 are the upper ends of links 69 and 71. Positioned between and pivotally connected to the lower ends of the links 69 and 71 by means of pins 72 are the upper ends of rail clamping or gripping arms 73 and 74, respectively. The upper ends 76 of the arms 73 and 74 are crossed as indicated and the opposite ends are provided with jaws 77 and 78. The gripping arms 73 and 74 are pivoted at the point of crossing by means of a bolt 79 having a castellated nut 81 and a cotter pin 82. The bolt 79 is secured to the box housing member at a point adjacent the lower end of the rod 61.

Secured to and extending upwardly from the sides of the block 63 adjacent the opening 64 are upstanding side straps 83 and 84. Mounted at the upper end of the straps 83 and 84 is a U-shaped handle 86 having a cross rod 87 for raising and lowering the block 63.

Mounted on the block 63, by means of a screw 88 adjacent one end thereof and between the straps 83 and 84, is a spring steel plate 89. The plate 89 has a hole therein of a size to freely pass the rod 61 when the plate is in a position normal to the axis of the rod 61 and for the walls thereof to bind about the rod 61 when the walls of the opening are out of 90° relation with respect to the axis of the rod 61.

The end of the plate 89 opposite the screw 88 is biased upwardly by means of a tension spring 91 connected thereto and to the side strap 84 as at 92 by any suitable means such as a cotter pin 93. Extending downwardly through an opening 95 in the U-shaped handle and through a suitable bearing 94 secured to the handle in axial alignment with the opening is a thumb actuated pin 96. The lower end of the pin 96 contacts the upwardly extending end of the plate 89, thus permitting the plate 89 to be depressed at will toward a position normal to the axis of the rod 61. While I have shown a spring steel plate 89 secured to the block 63, it will be apparent that a plate made of materials other than spring steel may be used by hingedly connecting the plate to the block 63.

From the foregoing description, the operation of my improved grapple will be readily understood. When the vehicle is not in position for using the derrick, such as when moving from place to place, the grapple arms 73 and 74 are moved to the raised or open position as shown in solid lines in Fig. 6 of the drawings. When the vehicle is in position for operation, the thumb actuated pin 96 is pressed down thus moving the plate 89 down to a position normal to the rod 61. The handle 86 is then raised, thereby moving the block 63 up and moving the gripping arms 73 and 74 to the lowered or clamping position as shown in dotted lines, Fig. 6. It will be noted that upon release of the pin 96 the spring 91 moves the plate 89 to a position out of 90° relation with respect to the rod 61 thereby locking the grapple assembly in closed position.

From the foregoing it will be seen that I have devised a derrick which is very simple of construction and operation and economical of manufacture. By employing a triangular shaped frame for the derrick I have greatly reduced the weight thereof, thus adapting it for quick and easy erection and removal from the railroad track.

Also, by constructing a derrick which is easily dismantled and erected with the boom extending in any desired direction, I have provided an extremely versatile derrick which may be set up in desired positions and operated by unskilled labor.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a derrick for use on a railroad track, a frame structure in the shape of a right triangle as viewed in plan comprising a base section overlying a rail of the track and parallel thereto, track engaging wheels rotatably mounted in tandem adjacent each end of the base section, a vertically extending mast mounted at one end of said base section, pairs of oppositely disposed clevises adjacent the upper and lower ends of the mast lying in a vertical plane normal to said base section, a side section detachably secured at one end to one of said clevises adjacent the lower end of said mast, a track engaging wheel at the other end of said side section mounted for rotation in a vertical plane parallel to said base section, sets of angularly disposed horizontally extending clevises adjacent the ends of said base and side sections opposite said mast, a diagonal section extending between and detachably secured to selected ones of the clevises on said base and side sections, a brace secured to the mast adjacent the top thereof and extending downwardly and secured to the end of said base section opposite the mast, a brace fixedly secured to the end of said side section opposite the mast and detachably secured to a selected one of the clevises at the upper end of the mast, a boom pivotally mounted adjacent the lower end of the mast, a guy rod pivotally connected to the upper end of the mast and secured to the boom adjacent the upper end thereof, and means for detachably anchoring the ends of said base and side sections opposite the mast to the railroad track.

2. In a derrick for use on a railroad track, a frame structure in the shape of a right triangle as viewed in plan comprising a base section, a vertically extending mast mounted at one end of the base section, a side section detachably secured at one end to the lower portion of said mast forming with said base section an included angle of approximately 90°, a diagonal section extending between and detachably connected to said base and side sections adjacent the ends thereof opposite said mast, a boom pivotally mounted adjacent the lower end of the mast, a guy rod pivotally connected to the upper end of the mast and secured to the boom adjacent the upper end thereof, a box-shaped housing open at the bottom thereof mounted beneath each corner of said triangular shaped structure, axles transversely disposed with respect to the longitudinal axis of the base section mounted in the said housings, a track engaging wheel rotatably mounted on each of said axles, and means detachably anchoring the corners of the frame adjacent the ends of said diagonal member to the railroad track.
